Primary Examiner — Khawaja Anwar*(74) Attorney, Agent, or Firm* — Lauff Law PLLC(57) **CLAIM**

The ornamental design for a interactive device holder, substantially as shown and described.

DESCRIPTION

FIG. 1 is a left front upper perspective view of the interactive device holder shown holding an interactive device depicted in broken lines;

FIG. 2 is a right front lower perspective view thereof; FIG. 3 is a right rear upper perspective view of the interactive device holder;

FIG. 4 is a left front upper perspective view thereof;

FIG. 5 is a right elevation view thereof;

FIG. 6 is a right rear lower perspective view thereof;

FIG. 7 is a left front lower perspective view thereof;

FIG. 8 is a front elevation view thereof;

FIG. 9 is rear elevation view thereof;

FIG. 10 is an upper plan view thereof;

FIG. 11 is a lower plan view thereof;

FIG. 12 is a right front upper perspective view thereof;

FIG. 13 is a left rear upper perspective view thereof;

FIG. 14 is a left elevation view thereof;

FIG. 15 is a right front lower perspective view thereof; and, FIG. 16 is a left rear lower perspective view thereof.

In the drawings, the broken lines are for the purpose of illustrating environment only and form no part of the claimed design.

1 Claim, 4 Drawing Sheets(56)
